UNITED STATES PATENT OFFICE.

MARTIN O. REHPUSS, OF PHILADELPHIA, PENNSYLVANIA, ASSIGNOR TO JOHN WANAMAKER, PHILADELPHIA, OF PHILADELPHIA, PENNSYLVANIA, A CORPORATION OF PENNSYLVANIA.

IMPRESSING MACHINE.

Application filed February 21, 1918. Serial No. 218,450.

To all whom it may concern:

Be it known that I, MARTIN O. REHPUSS, a citizen of the United States, residing in Philadelphia, Pennsylvania, have invented 5 an Impressing Machine, of which the following is a specification.

One object of my invention is to provide a relatively simple, substantial and conveniently operated machine for printing or 10 making an impression upon a sales slip or similar paper; the device being particularly adapted to allow of the easy insertion and removal of the plate upon which is carried the type, lettering, etc., from which an impression is to be made.

A further object is to provide a machine of the above noted character in which the parts shall be so arranged and constructed that it shall be conveniently portable and 20 shall be especially designed to receive address plates each having side or edge flanges projecting or formed at an angle to its general plane.

It is also desired to provide a novel detail 25 construction for the plate-carrying head and plunger with their associated parts, as well as a novel and relatively simple device for automatically feeding the inking ribbon under and in engagement with the plate from 30 which an impression is to be made.

The invention also contemplates the provision of a device for preventing the deposit of ink or coloring material from the ink ribbon upon the address plate, which device 35 includes a pair of spindles adjustably supporting a paper or other strip between said plate and ribbon.

These objects and other advantageous ends I secure as hereinafter set forth, reference being had to the accompanying drawings, in which

Fig. 1, is a side elevation of an impressing device constructed according to my invention,

Fig. 2, is a front elevation of the machine shown in Fig. 1.

Fig. 3, is a side elevation partly in vertical section on the line 3—3, Fig. 2.

Fig. 4, is a horizontal section on the line

50 4—4, Fig. 3,

Fig. 5, is a horizontal section on the line

5—5, Fig. 2, and

Fig. 6, is an inverted plan of the plate-carrying head.

In the above drawings, 1 represents a suitable supporting base having at its rear an upwardly and forwardly projecting standard which is vertically elongated under the front of said base to provide a guideway for a plunger 3. The top of this front portion 55 of the standard is forked for the reception of an operating lever 4 and this is journaled on a spindle 5 extending between the branches of said fork. The upper end of the plunger is provided with a rearwardly extending 60 arm 6 whose upper face is designed to be engaged by a cam-like extension 7 from the rear of the lower end of the handle, while its under face is at all times engaged by a coil spring 8 mounted in a vertically extending 65 recess of the standard 2. The lower end of the plunger 3 has fixed to it by a pin 11 a head 9 elongated from front to rear and whose under face has two parallel undercut grooves 10 extending also from front to 70 rear, for the reception of the turned over flanges α —1 of an address plate α . This latter preferably consists of an elongated piece of relatively stiff sheet metal having 75 pressed out from it letters or symbols constituting, in the present case, a business address or residence, and it is free to slide longitudinally of the head 9 in order to permit of its convenient insertion and removal. The upper face of said plate is designed to 80 be immediately adjacent or in close contact with that portion of the under face of the head 9 between the grooves 10.

The rear end of the head 9 is formed with two oppositely projecting lugs 12 to which 90 is fixed a transversely extending bar 13 (preferably by means of screws). The ends of this bar are turned up and, as shown in Fig. 5, have respectively fixed to them a pair of forwardly extending stationary spindles 95 14 whose front ends are threaded for the reception of thumb nuts 15. On each of these spindles is rotatably mounted a tube or sleeve 16 to whose rear end is fixed a ratchet wheel 17;—it being noted that each of said sleeves is longitudinally slotted in order that it may increase slightly in diameter when the thumb nut 15 is screwed upon its spindle so as to exert sufficient pressure upon its adjacent end. The nut and washer 100 15 also serve to removably retain on the sleeve a reel 19 holding a portion of the inking ribbon 20 which, as shown in Fig. 2, is designed

to extend from one of the reels across the under face of the head 9, over the plate 20 and then to the second reel.

Respectively below the spindles 14 the bar 13 carries two other spindles 18 on which is wound a paper strip or web of fabric 18^a extending from one of these auxiliary spindles, transversely across and in contact with the under surface of the address plate, to 10 the second auxiliary spindle. Said paper strip is thus interposed between said plate and the upper surface of the ink ribbon 20 and, as its spindles are rotatable, it may be drawn across the head from time to time so 15 that there will at all times be a clean surface adjacent the raised portion of the address plate.

For causing the inking ribbon 20 to be fed across the head 9, I mount a longitudinally 20 slideable bar 21 in a suitably formed transversely extending recess in the standard 2, preferably to the rear of the recess for the spring 8, and to the ends of this bar I pivot two oppositely hung pawls 23 which, under 25 the action of gravity, may rest upon the toothed edge of the ratchet wheels 17 respectively. Said bar 21 is of such length that when either of its pawls is in engagement with the side of the standard, the pawl 30 on its opposite end engages the teeth of the adjacent ratchet wheel. In order that the bar 21 with its pawls shall remain in a given position, I mount a set screw 24 in the standard in such position that it may be 35 turned into holding engagement with said bar at will.

With the above described arrangement of parts, any desired one of a number of address plates is inserted in the grooves 10 of 40 the head 9, and the sales slip, bill or other paper upon which it is desired to print or impress the address on said plate is placed under the head upon the flat upper face of the front portion of the base. If now the 45 lever or handle 4 is swung back and down, its cam projection 7 engages the arm 6 of the plunger 3, forcing this latter down in its guideway against the action of the spring 8 and ultimately causing the projecting 50 raised portions of the address plate to print upon the sales slip,—the ink ribbon 20 and the paper strip 18^a being of course interposed. Thereafter, as the lever 4 is released, the spring 8 acts to raise the plunger 3 to 55 its normal elevated position and just before the head 9 reaches its upper position, one of the pawls 23 strikes the teeth of its ratchet 17, forcing this with the attached tube 16 and the reel 19 to turn through a 60 part of one revolution. As a result a short length of the ribbon 20 is wound upon this reel and a corresponding length is drawn from the other reel whose movement is retarded to some extent by the friction exerted 65 upon it by its tube 16, whose central portion

has been slightly expanded for this purpose by setting up its thumb nut 15. A fresh portion of the ink ribbon is thus brought under the printing face of the address plate after each depression of the head 9, and the consequent winding of said ribbon upon one of the reels is continued until it is practically filled. The operator then loosens the set screw 24 and moves the bar 21 longitudinally in its recess until the second pawl 23 70 is brought into a position in which it will be engaged by its adjacent ratchet wheel. Since the teeth of the latter are disposed oppositely to those of the first ratchet wheel, the subsequent operation of the device will 75 reverse the direction of the movement of the ribbon, causing it to be wound up on the second reel. 80

It is particularly to be noted that the address plate may be inserted or removed 85 with the greatest ease and a succession of impressions made from any of a number of different plates without loss of time. By means of the paper or fabric strip between the plate and the ink ribbon, the former is 90 kept clean and as said strip becomes worn or filled with ink at any one point, it may be replaced by a fresh portion adjacent the address plate by turning one of the auxiliary spindles 18 to wind up a suitable length 95 thereof. In order to insure that the ink ribbon and paper strip shall be substantially flat over the face of the address plate, I provide two parallel guide bars 22 respectively on opposite sides of the head 9. Said 100 bars are shown as flat elongated plates spaced away from the sides of said head and mounted with their lower edges slightly above a horizontal plane including the raised portions of the address plate. With this arrangement the ink ribbon and paper strip on one side of the machine pass from their spindles over the lower edge of one of the guide bars 22, thence across the face of the address plate, over the second guide bar and 105 to their spindles on the opposite side of the machine. 110

Obviously the inking mechanism, consisting of the bars 13 and 21 with their attached parts, may be omitted without departing 115 from my invention, in which case the document operated on would be impressed by the address plate instead of printed.

I claim:

1. The combination in an impressing machine of a head having a member from which an impression is to be made, an ink ribbon on the head extending across said member with a strip of protective material also carried by the head and extending between the ink ribbon and the printing face of the impressing member; with means for operating the head to make an impression. 120
2. The combination in an impressing machine of a head having a member from 125

which an impression is to be made; a transversely extending bar mounted on said head; two pairs of spindles mounted on the bar respectively on opposite sides of the head; 5 a protective strip passing from a spindle on one side of the head, across said impression member to a second spindle on the op-

posite side of the head; and an ink ribbon extending between the two remaining spindles over said protective strip; with 10 means for actuating the head to make an impression.

In witness whereof I affix my signature.
MARTIN O. REHFUSS.
